UNITED STATES PATENT OFFICE.

CONRAD L. ROSENQVIST, OF YONKERS, NEW YORK, ASSIGNOR TO OTIS ELEVATOR COMPANY, OF JERSEY CITY, NEW JERSEY, A CORPORATION OF NEW JERSEY.

VIBRATION-ABSORBER FOR ALTERNATING-CURRENT-MAGNET ARMATURES.

1,014,257.

Specification of Letters Patent.

Patented Jan. 9, 1912.

Application filed August 21, 1908. Serial No. 449,687.

To all whom it may concern:

Be it known that I, CONRAD L. ROSENQVIST, a subject of the King of Sweden, residing in Yonkers, in the county of Westchester and State of New York, have invented a new and useful Improvement in Vibration-Absorbers for Alternating-Current-Magnet Armatures, of which the following is a specification.

10 The present invention relates to means for absorbing or counteracting mechanical vibrations in one body by transferring them to another, and is particularly adapted for use with alternating current electro-magnets 15 or other apparatus or parts of mechanism where it is desirable to stop or reduce the vibrations of certain parts.

An object of the invention is to provide means to reduce to a minimum the vibrations 20 set up in a body, as, for example, the armature core of an electro-magnet energized by a single phase alternating current.

It is well known that the armature or moving part of an electro-magnet energized 25 by a single phase alternating current vibrates more or less, due to the pulsating character of the current supplied to it. As these vibrations produce noise and cause considerable wear on the pins or center 30 screws which support the movable part of the magnet, it is desirable that these vibrations be reduced to a minimum, and I propose to accomplish this result by producing in an attached body a secondary set of vibrations that differ in magnitude and phase, but not in rate from those of the magnet. 35 This result may be secured by having attached to the armature or vibrating body an elastic vibratory transmitter having secured 40 to it a suitable counterweight.

Other objects of the invention will appear hereinafter, the novel combinations of elements being set forth in the appended claims.

Referring to the accompanying drawings, 45 in which are illustrated several forms of construction embodying my invention, Figure 1 is a side elevation of an electro-magnetic switch mechanism to which the invention is applied; Fig. 2 is a rear elevation of 50 the same; Fig. 3 is a side elevation of a modification; and Fig. 4 is a detail view of a modified form of the device for absorbing vibrations.

As shown in Figs. 1 and 2, a base-plate 1 55 of slate or other suitable insulating material

has secured to its front and rear faces, respectively, the bracket plates 2 and 3. A switch lever 4, pivoted at 5 to the bracket plate 2, carries at its upper end a contact 6 adapted to be moved into and out of engagement with a stationary carbon contact 7. The magnet frame 8 is preferably made of laminated soft iron and is formed with a central core 9 surrounded by the magnet coil 10. The armature 11, also made of laminated magnetic material, is carried by a lever 12 which extends through an opening in the base 1 and is pivoted at 13 to the bracket plate 2. A depending lug 14 on the lever 12 is adapted to strike a bolt or projection 15 on the switch lever 4 and open the switch when the armature is dropped. A coil spring 16 which bears against the lower end of the switch lever closes the switch when the armature 11 is in its attracted 75 position. A buffer 17 of leather, rubber, or other suitable material may be placed between the magnet frame and the armature lever 12 in position to hold the armature separated a slight distance from its magnet. 80 The magnet is adapted to be energized by a single phase alternating current, and in order to eliminate or reduce to a minimum the vibrations set up in the armature, I provide the following device. An elastic member 85 18 which as here shown is in the form of a flat metal spring curved into a U shape, has secured thereto at one end a counterweight 19. The other end of the elastic member is secured to the outer end of the 90 armature lever by means of a bolt 20. Now a weight supported in this manner, if moved so as to place the spring under tension and then released, will vibrate at a substantially 95 uniform rate, the amplitude of vibration gradually decreasing until the weight comes to rest. This normal rate of vibration depends on several factors, such as the length of the spring, mass of the weight, and strength or stiffness of the spring, and by 100 varying any of these factors the normal rate of vibration may be varied. The vibrations of the weight are transmitted through the spring and tend to produce vibrations in the support corresponding in rate, but not in 105 phase, with those of the weight. Also, vibrations of the support will be transmitted through the spring 18 to the counterweight 19 and cause it to vibrate if the rate of vibration of the support is the same as the normal 110

rate of vibration of the counterweight. In the present construction, the counterweight and elastic member are so designed that the normal rate of vibration will be the same as that of the armature, due to current alternations. The best results are obtained when the counterweight is lighter than the armature, and the elastic member 18 is so proportioned that the vibration or movement of the counterweight will be nearly in an opposite direction to that of the armature at any given time. With this arrangement it is evident that during the period of the cycle when the current is at or near the zero point, and the magnet tends to drop its armature, the stored energy of the counterweight is utilized to keep the armature in place until the next current impulse reaches the working value, and thus the tendency of the armature to vibrate is checked by the counter-vibrations of the weight 19.

In Fig. 3 I have shown another form of magnet to which my invention is applied. In this case the magnet frame 8' is secured to the base 1 by bolts 25. The armature 11' is pivoted at 26 to the magnet frame and is approximately vertical when in its attracted position. The stationary contact 6' of the switch is secured to the base 1, and the movable contact 7' is provided with a stem 27 extending through openings in the vertical extensions 28 and 29 of the magnet frame and armature, respectively. A coil spring 30 surrounds the stem 27 between the extension 28 and the contact 7' and normally holds said contact in engagement with the fixed contact 6'. A comparatively heavy coil spring 31 surrounding the stem 27 between the extensions 28 and 29 holds the pole pieces of the magnet and armature slightly separated and also serves to absorb or partially absorb the vibrations of the armature. When the magnet is deenergized, the armature swings outward about the pivot 26 and the extension 29 strikes the nuts 32 on the stem 27 and moves the contact 7' away from the fixed contact 6' to open the switch. The counterweight 19' and elastic member 18' are similar to the parts 18 and 19 of Fig. 1, but are arranged to permit the counterweight to vibrate in a horizontal direction instead of a vertical direction as in Fig. 1. In each case the weight is arranged to vibrate in the same direction as the armature or vibrating part to which it is attached.

In Fig. 4 is shown a modified form of the vibration absorber. The elastic member 18'' is in this instance a coil spring connected at one end to a counterweight 19'' and adapted to be connected at its opposite end to the armature or other vibratory member.

The particular forms of vibration absor-

ers shown are merely examples of the various forms which come within the scope of the present invention. The elastic member may be made in many different ways and forms other than those shown on the drawing. The point of attachment of the elastic member to the vibrating part may also be varied within wide limits. It will be understood further that the invention may have a much wider application than to alternating current magnets alone, as in general it may be adapted to counteract vibrations set up in a solid body from whatever cause. Furthermore, I wish not to be limited to the particular features of construction shown, as various changes in details and arrangement of parts may be made without departing from the spirit and scope of the invention.

What I claim as new and desire to secure by Letters Patent of the United States is:

1. The combination with a vibratory member, of electro-magnetic means for producing a uniform rate of vibrations therein, and an attached body having the same normal rate of vibration as said member and adapted to vibrate in opposition thereto.

2. The combination with a vibratory member, of electro-magnetic means for producing vibrations therein, and an attached vibratory body having the same rate of vibrations as said member but differing in phase.

3. The combination of an electro-magnet adapted to be energized by an alternating current, and a mechanical device connected thereto and adapted to decrease the mechanical vibrations in said electro-magnet by means of counter-vibrations.

4. The combination with an alternating current magnet and its armature, of a weight, and an elastic vibration transmitter connecting said weight and armature.

5. The combination with an alternating current electro-magnet, a vibratory body, and means for reducing the vibrations of the electro-magnet due to current alternations by transmitting counter vibrations from said body to the electro-magnet.

6. The combination with an electro-magnet adapted to be vibrated by an alternating current, a vibratory body, and means for reducing the vibrations of the magnet by producing in said body counter vibrations differing in phase from those of the magnet.

In testimony whereof, I have signed my name to this specification in the presence of two subscribing witnesses.

CONRAD L. ROSENQVIST.
